A. DANDRIEUX

MACHINE FOR SHARPENING PENCILS

Original Filed May 22, 1922

UNITED STATES PATENT OFFICE.

AUGUSTE DANDRIEUX, OF PARIS, FRANCE, ASSIGNOR TO SOCIÉTÉ ANONYME ANCIENS
ATELIERS A. DANDRIEUX, OF PARIS, FRANCE.

MACHINE FOR SHARPENING PENCILS.

Application filed May 22, 1922, Serial No. 562,786. Renewed September 27, 1923.

To all whom it may concern:

Be it known that I, AUGUSTE DANDRIEUX, a citizen of the French Republic, residing at 11 Rue Tournefort, Paris, France, have invented new and useful Improvements in Machines for Sharpening Pencils, of which the following is the specification.

This invention relates to a machine for sharpening pencils in which the sharpening member is constituted by a circular plate carrying radial blades and rotating about an axis at right angles to its plane and such that the trace of the plate and the projection of the axis of the pencil on a plane parallel to the latter, and passing through the axis of the plate, form between them an angle equal to that of a generatrix with the axis of revolution of the cone formed at the end of the pencil after sharpening.

20 A form of carrying out the present invention is illustrated by way of example in the accompanying drawing, in which:

Fig. 1 is a perspective view of the whole of the machine.

25 Fig. 2 is a vertical section of the machine, the casing and centering device being removed.

Figs. 3 and 4 illustrate, in four different half-sections, the centering device for the pencil:

(a) Figure 3, left hand part; half elevation of the whole of the centering apparatus, the casing and cover being cut away.

(b) Fig. 3, right hand part, half section 35 through a diametral plane.

(c) Fig. 4, left hand part, half section of the cover and of the device integral therewith through a diametral plane at right angles to the previous one.

40 (d) Fig. 4, right hand part, corresponding half section, the cover alone being cut away.

Fig. 5 is an elevation of the cam.

45 Fig. 6 is a vertical section of the block supporting the axis of rotation of the blade plate and directing or guiding the pencil.

Fig. 7 is a corresponding elevation, showing the device for adjusting the length according to which the pencil is to be sharpened.

Fig. 8 is an elevation of the blade carrying plate.

A circular plate 1 carries blades 2, arranged according to radii forming between them angles which are preferably equal, but may also be different. In the present form of construction, these blades are made in one piece with the plate whether the whole is cast or stamped in the hot state and the blades are sharpened flatwise; the plate is provided with a frustum-shaped projection 3 perforated at its center with an elongated hole 4, so that this plate may be integral for rotation with a shaft 4 bearing a flat part 5. This shaft is threaded at its end 6 and receives a nut 7 for securing the plate 1 by means of a spring 8 adapted also to hold the flat part of the blades in contact with a plane face 9 of a block 10 through which passes the shaft 4 and serving as a bearing 70 for the latter. The shaft 4 is also threaded at its other end, so as to permit of securing thereon a cam 11 by means of a nut 12.

The cylindrical bore 14 of the block 10 which receives the shaft 4 has its axis at 75 right angles to the plane face 9 on which rub the blades. The block 10 is provided, moreover, with a conical bore 13, the projection of the axis of the cone on a plane parallel to it and passing through the axis 80 of the bore 14 makes, with the trace of the surface 9 on this plane, an angle which will be equal to the angle formed by a generatrix and the axis of revolution of the cone cut at the end of the pencil.

85 The axis of the bore 13 makes with the plane surface 9 an angle smaller than that it makes with a generatrix of the bore and is placed in such a manner that the surface 9 intersects the conical surface of the bore 13 of which it contains the apex. It results therefrom that this bore opens on the surface 9 by an opening limited by two non-parallel straight lines. The bore 13 being terminated at its upper part by a cylindrical portion, the opening is closed on this side by an arc of ellipsis; moreover, it might not be closed.

90 On the other hand, the block 10 is secured on a sheet-iron frame 45, by screws 15 or by 100

any other suitable means; besides, the nut 7 is provided with a circular projection with flat parts 16, on which a crank 17 is secured by means of a milled nut 18.

5 On a lug 19 of the frame 45 is mounted a wheel 20 perforated with a central hole and directly receiving a rotary movement from the cam 11 in the following manner:

The cam 11 is formed of three equal arcs 10 of circumference, but the centres of which are at the apex of an equilateral triangle; these arcs are terminated by segments of radius. In the present form of construction, they are obtained by embossing of the plate 15 11. Between two arcs is provided a determined space, equal to the thickness of a tooth of the wheel 20. This wheel is formed with such teeth that their sides and that of the cam, when they are in contact, have the 20 same tangent plane at the point of contact.

Consequently for a rotation of $\frac{2}{3}\pi$ of the cam 11 the wheel 20 rotates to the extent of one tooth; the speed of this wheel is therefore obviously a function of its number 25 of teeth. It is moreover possible to replace the cam and toothed wheel device which has just been described by any other system giving the same result and in particular by a suitable hyperbolic gearing.

30 In the central cylindrical bore of the wheel 20 is mounted a centering device for the pencil. The pencil is clamped between two rolls 21 having the shape of a solid obtained by putting together the small bases 35 of two conic frusta; these two rolls are each mounted on an axis 22 to the ends of which are pivoted arms 23 pivoted together at 24 and arms 25 integral with lug levers 26 pivoted at 27. On each of the axes 27 is mounted 40 a returning spring 28 which tends to space apart both lugs 26 and consequently to bring together the rolls 21 clamping the pencil between them. The whole is mounted on a frame 29 made integral with the 45 cover by the lugs 26; this cover is secured by screws on a casing 31 the lower cylindrical part 32 of which is forced into the cylindrical bore of the wheel 20.

The operation is as follows:

50 *Centering of the pencil.*—It suffices to force the pencil within the centering device; the pencil is guided by the bore 13 and by the rolls 21 which clamp it between them. These rolls are provided with circular projections which cause the pencil to participate to the rotary movement of the device.

55 *Sharpening.*—By turning the crank 17, the cutters 2 successively come in front of the opening through which opens the bore 60 13 and cut the wood extending outward, exerting at the same time a tractive stress tending to move the pencil forward. Simultaneously, the cam 11 rotates and drives the wheel 20. The pencil is automatically 65 subjected to a rotary movement about its

axis, the speed of which is always in relation with that of the blade-carrying plate, and a movement of translation in the direction of its axis. Consequently, the pencil is sharpened according to a conical surface of 70 revolution. This arrangement does away with any automatic feeding system, the feeding movement being obtained by the tractive stress of the blades cutting the 75 wood.

An adjustable abutment device is provided allowing to sharpen the pencil with a more or less fine point. A rod 33, forming a hook at 34, is provided with a notch constituting two steps at 35; these steps can be brought under the point of the pencil, so as to limit its downward movement. The rod 33 is bent so as to form three folds 36 in order to constitute indentments determining the position of the notch 35 when abutting against the wall of the block 10 against which the slightly resilient rod 33 is pressed, a screw 37 holds this rod on the frame 45, by an elongated hole 38 forming a slide. The rod can slide, moreover, through a hole 39 provided in the frame and having the same cross-section as the rod.

This device also serves to discharge the broken leads which eventually obstruct the bore 13; it suffices to impart to the rod 33 a rapid to and from movement to crush the broken lead into small fragments which fall in the drawer 40 adapted to receive the 90 chips and to easily drive them away.

The apparatus is enclosed in an outer casing 41; this casing is provided with a circular opening into which is forced a disc 43, made of mica or any other translucent material, mounted in a circular armature 44 allowing one to see the blade carrying plate. These arrangements which are simply used for protecting the parts and for aesthetic purposes may obviously receive any suitable forms. The casing 41 bears at its lower part 100 on the support 42 integral with the frame 45 110 on which it is secured by screws or any other means.

The blade-carrying plate might be replaced by any other rotating member allowing to sharpen by cutting or wearing down the end of the said pencil according to a cone, this member having its axis of rotation inclined in such a manner that the projection of the axis of the pencil on a plane parallel to this axis passing through the axis of rotation of the sharpening member, makes with a perpendicular raised on this latter axis and in this plane, an angle equal to the angle of a generatrix with the axis of 120 the cone, after sharpening.

Besides, it is possible to obtain a variable inclination of the blade-carrying plate relatively to the axis of the pencil, so as to modify the cone cut at the end of the pencil, 130 according to the nature of the latter, by any

suitable device permitting to give to the axis 4 angular displacements in a vertical plane.

What I claim as my invention and desire to secure by Letters Patent is:

- 5 1. In a machine for sharpening pencils, a circular plate, radial blades carried by the said plate and the sharp edges of which are in the same plane, an axis of rotation at right angles to this plane and on which the 10 said plate is rigidly secured, a frame supporting the said axis, a surface of this frame coinciding with the plane of the blades, a conical hole in this frame, opening laterally on the said surface, a cylindrical socket 15 mounted on the frame so as to be capable of rotating about its axis which coincides with that of the conical hole, a support within this socket, two opposite clips pivoted on this support, means for resiliently bringing back these two clips, means for 20 coordinating their displacements for rendering them symmetrical relatively to the axis of the socket, means for rotating the blade-carrying plate, means for rotating the 25 pencil about its axis.
2. In a machine for sharpening pencils, a circular plate, radial blades carried by the said plate and the sharp edges of which are in the same plane, an axis of rotation at right angles to this plane and on which the 30 said plate is rigidly secured, a frame supporting the said axis, a surface of this frame coinciding with the plane of the blades, a conical hole in this frame, opening 35 laterally on the said surface, a cylindrical socket mounted on the frame so as to be capable of rotating about its axis which coincides with that of the conical hole, a support within this socket, two opposite 40 clips pivoted on this support, means for resiliently bringing back these two clips, equal levers pivoted on the clips and together, slides of the said inner support, through which pass the pivoting axes connecting the levers together, rolls in the shape of a double frustum carried by the 45 clips, circular ribs on the said rolls rendering the pencil integral with the socket for the rotary movement, means for rotating the blade-carrying plate, means for rotating the pencil about its axis.
3. In a machine for sharpening pencils, a circular plate, radial blades carried by the 50 said plate and the sharp edges of which are in the same plane, an axis of rotation at right angles to this plane and on which the said plate is rigidly secured, a frame supporting the said axis, a surface of this frame coinciding with the plane of the blades, a conical hole in this frame, opening 55 laterally on the said surface, a cylindrical socket mounted on the frame so as to be capable of rotating about its axis which coincides with that of the conical hole, a support within this socket, two opposite 60 clips pivoted on this support, means for resiliently bringing back these two clips, equal levers pivoted on the clips and together, slides of the said inner support, through which pass the pivoting axes connecting the levers together, rolls in the shape of a double frustum carried by the 65 clips, circular ribs on the said rolls rendering the pencil integral with the socket for the rotary movement, means for rotating the blade-carrying plate, means for resiliently bringing back these two clips, equal levers pivoted on the clips and together, slides on the said inner support, 70 through which pass the pivoting axes connecting the levers together, rolls in the shape of a double frustum carried by the clips, circular ribs on the said rolls rendering the pencil integral with the socket for the rotary movement, means for rotating the blade-carrying plate, means for rotating the 75 socket.
4. In a machine for sharpening pencils, a circular plate, radial blades carried by the said plate and the sharp edges of which are in the same plane, and axis of rotation at right angles to this plane and on which the said plate is rigidly secured, a frame supporting the said axis, a surface of this 80 frame coinciding with the plane of the blades, a conical hole in this frame, opening laterally on the said surface, a cylindrical socket mounted on the frame so as to be capable of rotating about its axis which coincides with that of the conical hole, a support within this socket, two opposite 85 clips pivoted on this support, means for resiliently bringing back these two clips, equal levers pivoted on the clips and together, slides of the said inner support, through which pass the pivoting axes connecting the levers together, rolls in the shape of a double frustum carried by the 90 clips, circular ribs on the said rolls rendering the pencil integral with the socket for the rotary movement, a screw thread on the axis of rotation of the plate, a nut, a spring taking a bearing on this nut and on the plate, a polygonal projection on this nut, a 95 crank mounted on this projection, a locking nut for the crank, means for transmitting the rotation from the axis of the plate to the socket.
5. In a machine for sharpening pencils, a circular plate, radial blades carried by the said plate and the sharp edges of which are in the same plane, an axis of rotation at right angles to this plane and on which the said plate is rigidly secured, a frame supporting the said axis, a surface of this frame coinciding with the plane of the blades, a conical hole in this frame, opening 100 laterally on the said surface, a cylindrical socket mounted on the frame so as to be capable of rotating about its axis which coincides with that of the conical hole, a support within this socket, two opposite 105 clips pivoted on this support, means for resiliently bringing back these two clips, equal levers pivoted on the clips and together, slides of the said inner support, through which pass the pivoting axes connecting the levers together, rolls in the shape of a double frustum carried by the 110 clips, circular ribs on the said rolls rendering the pencil integral with the socket for the rotary movement, a screw thread on the axis of rotation of the plate, a nut, a spring taking a bearing on this nut and on the plate, a polygonal projection on this nut, a 115 crank mounted on this projection, a locking nut for the crank, means for transmitting the rotation from the axis of the plate to the socket.
6. In a machine for sharpening pencils, a circular plate, radial blades carried by the said plate and the sharp edges of which are in the same plane, an axis of rotation at right angles to this plane and on which the said plate is rigidly secured, a frame supporting the said axis, a surface of this frame coinciding with the plane of the blades, a conical hole in this frame, opening 120 laterally on the said surface, a cylindrical socket mounted on the frame so as to be capable of rotating about its axis which coincides with that of the conical hole, a support within this socket, two opposite 125 clips pivoted on this support, means for resiliently bringing back these two clips, equal levers pivoted on the clips and together, slides of the said inner support, through which pass the pivoting axes connecting the levers together, rolls in the shape of a double frustum carried by the 130 clips, circular ribs on the said rolls rendering the pencil integral with the socket for the rotary movement, a screw thread on the axis of rotation of the plate, a nut, a spring taking a bearing on this nut and on the plate,

a polygonal projection on this nut, a crank mounted on this projection, a locking nut for the crank, a cam rigidly secured on the axis of rotation of the plate, a toothed wheel rigidly secured on the socket and combined with the said cam.

6. In a machine for sharpening pencils, a circular plate, radial blades carried by the said plate and the sharp edges of which are in the same plane, an axis of rotation at right angles to this plane and on which the said plate is rigidly secured, a frame supporting the said axis, a surface of this frame coinciding with the plane of the blades, a conical hole in this frame, opening laterally on the said surface, a cylindrical socket mounted on the frame so as to be capable of rotating about its axis which coincides with that of the conical hole, a support within this socket, two opposite clips pivoted on this support, means for resiliently bringing back these two clips, equal levers pivoted on the clips and together, slides of the said inner support, through which pass the pivoting axes connecting the levers together, rolls in the shape of a double frustum carried by the clips, circular ribs on the said rolls rendering the pencil integral with the socket for the rotary movement, a screw thread on the axis of rotation of the plate, a nut, a spring taking a bearing on this nut and on the plate, a polygonal projection on this nut, a crank mounted on this projection, a locking nut for the crank, a cam rigidly secured on the axis of rotation of the plate, a toothed wheel rigidly secured on the socket and combined with the said cam, means for adjusting the length of cutting or sharpening of the pencil lead.

7. In a machine for sharpening pencils, a circular plate, radial blades carried by the said plate and the sharp edges of which are in the same plane, an axis of rotation at right angles to this plane and on which the said plate is rigidly secured, a frame supporting the said axis, a surface of this frame coinciding with the plane of the blades, a conical hole on this frame, opening laterally on the said surface, a cylindrical socket mounted on the frame so as to be capable of rotating about its axis which coincides with that of the conical hole, a support within this socket, two opposite clips pivoted on this support, means for resiliently bringing back these two clips, equal levers pivoted on the clips and together, slides of the said inner support, through which pass the pivoting axes connecting the levers together, rolls in the shape of a double frustum carried by the clips, circular ribs on the said rolls rendering the pencil integral with the socket for the rotary movement, a screw thread on the axis of rotation of the plate, a nut, a spring taking a bearing on this nut and on the plate, a polygonal projection on this nut, a crank

mounted on this projection, a locking nut for the crank, a cam rigidly secured on the axis of rotation of the plate, a toothed wheel rigidly secured on the socket and combined with the said cam, a movable rod, notches of different depths in this rod, means for guiding and locking the said rod.

8. In a machine for sharpening pencils, a circular plate, radial blades carried by the said plate and the sharp edges of which are in the same plane, an axis of rotation at right angles to this plane and on which the said plate is rigidly secured, a frame supporting the said axis, a surface of this frame coinciding with the plane of the blades, a conical hole in this frame, opening laterally on the said surface, a cylindrical socket mounted on the frame so as to be capable of rotating about its axis which coincides with that of the conical hole, a support within this socket, two opposite clips pivoted on this support, means for resiliently bringing back these two clips, equal levers pivoted on the clips and together, slides of the said inner support, through which pass the pivoting axes connecting the levers together, rolls in the shape of a double frustum carried by the clips, circular ribs on the said rolls rendering the pencil integral with the socket for the rotary movement, a screw thread on the axis of rotation of the plate, a nut, a spring taking a bearing on this nut and on the plate, a polygonal projection on this nut, a crank mounted on this projection, a locking nut for the crank, a cam rigidly secured on the axis of rotation of the plate, a toothed wheel rigidly secured on the socket and combined with the said cam, a movable rod, notches of different depths in this rod, slides on the frame, projections carried by the said rod permitting the locking of the same.

9. In a machine for sharpening pencils, a circular plate, radial blades carried by the said plate and the sharp edges of which are in the same plane, an axis of rotation at right angles to this plane and on which the said plate is rigidly secured, a frame supporting the said axis, a surface of this frame coinciding with the plane of the blades, a conical hole in this frame, opening laterally on the said surface, a cylindrical socket mounted on the frame so as to be capable of rotating about its axis which coincides with that of the conical hole, a support within this socket, two opposite clips pivoted on this support, means for resiliently bringing back these two clips, equal levers pivoted on the clips and together, slides of the said inner support, through which pass the pivoting axes connecting the levers together, rolls in the shape of a double frustum carried by the clips, circular ribs on the said rolls rendering the pencil integral with the socket for the rotary movement, a

screw thread on the axis of rotation of the plate, a nut, a spring taking a bearing on this nut and on the plate, a polygonal projection on this nut, a crank mounted on this projection, a locking nut for the crank, a cam rigidly secured on the axis of rotation of the plate, a toothed wheel rigidly secured on the socket and combined with the said

cam, a movable rod, notches of different depths in this rod, slides on the frame, projections carried by the said rod permitting the locking of the same, a casing enclosing the whole, a drawer for receiving the chips.

In testimony whereof I have signed my name to this specification.

AUGUSTE DANDRIEUX.
